BLAST FURNACE

John S. Stewart, New York, N. Y.

Application March 17, 1943, Serial No. 479,501

11 Claims.

(Cl. 266—25)

This invention relates to blast furnaces of the general type comprising a vertical stack or shaft adapted to contain the charge of material—ore, sinter or scrap—to be smelted and which latter in its descent through the stack is heated to smelting temperature by blasts of air discharged from tuyères located in the lower portion of the stack and operated under sufficient pressure to inject the air into the column of charge and create an incandescent smelting zone adjacent its center.

Heretofore in blast furnace design, it has been conventional to constrict the furnace in the vicinity of the tuyère plane—i. e., the horizontal plane intersecting the discharge nozzles of the tuyères. That is, the furnace above the tuyères is usually expanded upwardly and outwardly forming what is known as a "bosh," and often this taper is carried all the way up to the charging floor at the top of the stack.

Such furnaces, because of their upwardly expanding diameter, are subject to the disadvantage that the descent of the charge in the stack is slowed down and the velocity and pressure of the ascending combustion gases are likewise retarded. Furthermore, the bosh because of such taper, defines skewbacks upon the base of the stack against which the charge in its semi-fused state can lodge, eventually forming an arch overlying the smelting zone and blocking the stack passageway.

It is well known that after a furnace has been in operation for a short time accretions begin to collect on the bosh, these accretions forming shelves upon which additional deposits continue to build, and gradually increase in thickness and height. Finally there remains only a restricted opening near the center of the column of charge in the nature of a crack of varying width extending from the tuyère plane upwardly to the top of the charge column. Subsequently, at some place or places in the furnace this crack bridges over so as to form an arch overlying the smelting zone. Such an arch, besides preventing the free descent of the charge in the stack, interferes with the uniform and equal distribution of the hot combustion gases therethrough, with the result that eventually a portion of the furnace goes "dead" and ceases to smelt. Under these dead spots air pockets fed from several tuyères may form and develop ruptures, known as "blow-holes," extending to the top of the charge column. At other localities in the furnace the charge may become choked with fine ore or other material and with accretions so that it loses its

air-permeability with a consequent diminution of the air supply.

Under such conditions, the charge subsides very slowly and, because of its longer exposure to the hot ascending combustion gases, the smelting zone rises higher and higher in the stack, producing what is known as "hot tops." Such hot tops result in unsatisfactory furnace performance as evidenced by reduced output, loss of metal by volatilization, and additional metal losses in the "cold" slags accompanying such faulty operation.

It is an important object of the present invention to provide a blast furnace of the above type which is so constructed and arranged as to overcome the foregoing disadvantages. More particularly, this object is attained by providing the furnace at the lower end of the stack with an enlarged smelting chamber, the transverse cross-sectional area of which on the tuyère plane is appreciably greater than the corresponding area for any horizontal plane intersecting the stack—this being the reverse of usual blast furnace design in which the stack ordinarily increases in width above the tuyère plane to form the bosh.

Another object of the invention is to provide a blast furnace of the above character so constructed and arranged as to accelerate the downward movement of the furnace charge through the stack, and more especially to prevent the charge from bridging over the smelting zone with the consequences previously explained.

Another object of the invention is to provide a blast furnace of the above character having an enlarged smelting chamber and means for discharging a large volume of air therein for effecting the intense and rapid smelting of the furnace charge, and thus increasing the operating capacity of the furnace.

Still another object of the invention is to provide a blast furnace of the above character including means for increasing the blast pressure in the stack in order to blow out the ore particles or "fines" which otherwise would accumulate on the wall of the stack.

The invention has a further object to provide a blast furnace of the above character in which the tuyères are so located with respect to the smelting chamber as to insure that the smelting zone is confined entirely within the chamber without extending up into the smaller area of the stack.

More particularly the invention aims to accomplish the above objects by providing a blast furnace generally of the form of an inverted funnel, the upwardly and inwardly tapered

tion of which defines the smelting chamber and the upright tubular portion, the stack. The wall of the smelting chamber preferably is inclined at an angle somewhat greater than the angle of repose of the furnace charge so as to insure close confinement of the charge within the chamber. By reason of the greater value of the smelting chamber relative to the stack per unit of height, and because of the larger smelting zone thereby provided, the subsidence of the charge within the shaft takes place more rapidly than in blast furnaces of conventional boshed design. As a result, there is less opportunity for the combustion zone to rise within the shaft, causing "hot tops" and loss of metal by volatilization, which further results in cold slags. Also, because the stack is smaller in transverse cross-section than that of the smelting chamber, a stronger flow of combustion gases will be forced up the stack to carry off the fines that tend to collect on the wall of the stack and clog the passageway.

Other objects and advantages will be apparent from the following detailed description of a preferred embodiment of the invention, reference being had to the annexed drawings, in which:

Figure 1 shows in vertical cross-section a schematic view of a blast furnace of a type suitable for the reduction of sintered lead sulphide ores and other lead-bearing materials;

Figure 2 is an enlarged vertical cross-sectional view through the smelting chamber of the furnace of Fig. 1;

Figure 3 is a plan of the furnace; and

Figure 4 is a transverse cross-sectional view taken on the tuyère plane through a blast furnace of modified shape.

The blast furnace schematically shown in the drawings comprises generally a smelting chamber 1, an upright stack 2 rising centrally from the top of the smelting chamber and having its upper end communicating through a ring 3 located in the charging floor 4 with a conical hood 5. The hood 5 leads upwardly into a chimney 6 venting to the atmosphere. A chute 7 extends downwardly at an angle, passing through the hood, for feeding charges of material to be smelted into the furnace from a bin or charge skip, the discharge spout of which is indicated at 8.

In accordance with usual blast furnace practice, the stack and smelting chamber are maintained substantially full of the furnace charge C. The furnace charge may consist of ore, sinter, scrap metal or other metal-bearing ingredients, and fluxes, coke or other solid reducer. For maintaining combustion to effect the smelting of the ore, air blasts are directed into the smelting chamber and into the body of the charge occupying the chamber from a series of tuyères 9 leading off from a bustle pipe 10 encircling the furnace and connected at 10a with a source of air under pressure.

The stack and smelting chamber may be of any suitable shape in transverse cross-section, but ordinarily will be circular, as indicated in Fig. 3. The walls of the stack and the smelting chamber may be composed of hollow metal sections 1a secured together side-by-side (Fig. 3) and forming jackets through which cooling water is circulated to prevent their burning out. The furnace rests upon a hearth 11 forming a shallow crucible 12 from which molten metal is removed through a well 13. For drawing off slag, a tap 14 is provided through the wall of the smelting chamber above the hearth level.

A branch conduit 15 leads off from the chimney

6 and opens into the top of a cyclone type of dust-separator 16. A conduit 17 extends from the top of the separator to a bag house (not shown). Within the branch connection 15, and also within the chimney 6 above the point of connection of the branch therewith, are wing dampers 18 and 18a, respectively, which may be so adjusted as to route the furnace gases either directly up the chimney to the atmosphere (as will be the case when starting up the furnace) or through the separator 16. The separator removes the dust and fines carried over from the furnace in the combustion gases and the separated material spilling from the lower end of the separator may be collected in cars 19 or in any other suitable receptacle. The fines may then be sintered or agglomerated in any well-known manner and returned to the furnace.

The smelting chamber tapers upwardly and inwardly from the hearth at an angle of approximately 65 degrees to the point of its junction with the base of the stack. The enlarged smelting chamber thus provided affords space for accommodating a large quantity of coke. Likewise the increased diameter of the smelting chamber allows more tuyères 9 to be arranged about its circumference with their discharge nozzles opening into the chamber on the tuyère plane 3-3 for supplying an abundance of air to the coke. This results in creating a large, intensely hot smelting zone S within the ore body filling the smelting chamber.

The number of tuyères 9 will be determined largely by the size of the furnace which in turn governs the size of its smelting zone. Most of the tuyères are set at right angles to the wall of the smelting chamber so as to direct their air blasts downwardly toward the hearth, while a few others with slag escapes are arranged horizontally serving, in addition to feeding air into the chamber, as overflow means to warn the furnace-man of the rising pool of slag so that he may open the tap 14 before the tuyères become fouled with slag. It is important that the tuyères be located in the vicinity of the bottom of the chamber—ordinarily on a level not exceeding 25% to 30% of the height of the chamber—in order that the smelting zone S produced by the air blasts is maintained near the bottom of the chamber and sufficiently far below the base of the stack to prevent it from creeping up into the stack during the operation of the furnace.

By inclining the wall of the smelting chamber at an angle of approximately 65 degrees, which is slightly more than the angle of repose of the furnace charge, the entire space of the chamber is kept filled with the charge and this condition is further aided by the weight of the charge column in the stack. Such an angle also lends proper proportion to the furnace when the furnace is designed with suitable regard to the volumetric relationship between the smelting chamber and the stack. That is, for assuring the descent of the charge through the stack at the most efficient rate of travel, the ratio between the volume of that part of the smelting chamber included between the tuyère plane and the base of the stack and the volume of the stack for a corresponding rise in height, should be approximately 2.73:1.00. Likewise the vertical distance between the tuyère plane and the base of the stack, as compared with the diameter of the stack, should bear a relationship of about 1.00:0.78. These ratios are approximate for blast furnaces of circular transverse cross-section and are subject to variation within reasonable limits.

However, this volumetric relationship of smelting chamber to stack is important for the additional reason that it fixes the location of the smelting zone far enough below the base of the stack to avoid the extension of this zone, during the operation of the furnace, up into the stack.

In the form of blast furnace just described the increased size of the smelting chamber provides for contact of a large volume of coke with a large volume of combustion air so as to produce a large, high-temperature zone of combustion. This results in a high CO concentration, rapid smelting and relatively low metal losses in the slag. Also the enlarged smelting chamber, because it provides for a greater amount of furnace charge per unit of jacket surface in comparison with present blast furnaces, results in more economical operation due to less heat dissipation and hence lower coke consumption. The increased hearth area permits a larger storage of slag, and hence allows a longer interval between successive slag tappings, which makes for a better settling of the slag, allows more time for the reduction of the metal compounds therein, and leads to more uniform temperature conditions within the furnace.

Because of the difference in cross-sectional area of the stack and smelting chamber, the charge will descend rapidly in the stack and spread out in thin layers in the smelting chamber, thus assuring a better and more intimate mixture of the charge. As a result of the faster descent of the charge through the shaft, the shaft may be made shorter in length than in blast furnaces built according to present practice.

An advantage which follows from having the tuyères 9 enter the smelting chamber through its upwardly and inwardly inclined wall, preferably approximately perpendicular thereto, is that this overcomes to a large extent the tendency to clogging of the tuyères. Heretofore, in the usual bosh which inclined upwardly and outwardly, considerable difficulty was encountered in maintaining the tuyères open because of the flow of the slag on the wall of the smelting chamber downwardly into the open ends of the tuyères. By reason of the overhanging wall of the smelting chamber in my furnace, the slag cannot drop into or build up around the nozzles of the tuyères. The air injected through the tuyères is under sufficient pressure to force its way well into the bottom of the column of charge, thereby causing intensive combustion of the coke and rapid oxidation of the sulphides. This generates a high temperature within the charge which rapidly melts the ore and creates a large percentage of CO for the reduction of the oxides.

Due to the increased number of tuyères, a large volume of air is fed to the smelting chamber, and consequently a large reduction zone is created within the body of the furnace charge. And because this relatively large volume of air must escape through the stack of small cross-sectional area a strong draft will be created upwardly through the charge filling the stack so as to carry off the fines that otherwise would tend to clog the passageway or build up as accretions on the stack wall. These fines, as has already been explained, are recovered in the separator 16.

Other advantages of the blast furnace just described are as follows:

The smaller area of the shaft compared with shafts of present blast furnaces of the same capacity allows a simpler mode of charging, doing away with spreaders, expensive charge cars, etc., and permits the use of a simpler and cheaper

form of hood for the top of the stack to give a smoke-free atmosphere on the charging floor. The elimination of the usual bosh obviates the conditions contributing to the formation of accretions, bridges, hot tops and blow-holes. Furthermore the cost of construction and operation of the furnace is less than for blast furnaces of equal capacity built according to present practice, and the requirements as to hoisting, handling and other auxiliary equipment are less.

The furnace need not be circular in shape. In Fig. 4 is disclosed a cross-sectional view of a furnace of modified form taken on the tuyère plane through its smelting chamber. As indicated in this figure the contour of the smelting chamber is that of a flattened oval as is also that of the stack 2', indicated in phantom outline. In this form of the furnace the same general relationships hold true; that is, the wall of the smelting chamber tapers upwardly and inwardly from the hearth to the base of the stack to provide for an enlarged smelting zone, and the plane of the tuyères 9' is located not substantially more than 25% to 30% of the height of the chamber in order to confine the smelting zone entirely within the chamber. Manifestly the furnace may be of rectangular or any other shape in cross-section as may be found most satisfactory or desirable.

I am aware that it has heretofore been proposed to provide furnaces with an enlarged hearth area, as exemplified by the heap furnace disclosed in the early patent to C. W. Munson, No. 983,833. Such furnaces, however, are not intended for nor are they capable of carrying out blast furnace operations. I am also aware that it has been proposed to design blast furnaces so that their circumferences gradually taper upwardly and inwardly throughout the major portion of their length, but in such furnaces the angle of taper is insufficient to materially affect the rate of subsidence of the furnace charge or the flow of the current of combustion gases through the stack, and these furnaces otherwise fail to accomplish the many objects I have above explained.

Manifestly various changes in structure and design may be made in the form of smelting furnace described above, which is to be regarded as exemplary and not restrictive of the invention, without departing from the spirit of my invention as defined by the following claims.

I claim:

1. A blast furnace comprising a smelting chamber, a vertical shaft extending upwardly from said chamber, said shaft and chamber being adapted to receive and confine a charge of material to be smelted, an opening for charging material into the top of said shaft to substantially fill the shaft and chamber, a series of tuyères discharging through the wall of the chamber in a tuyère plane located sufficiently below the base of the stack as to avoid extension of the smelting zone from the chamber into the stack, and means for withdrawing slag and molten metal from the bottom of said chamber, said chamber having its wall tapered upwardly and inwardly between the tuyère plane and the base of the stack at an inclination such as to embrace and confine the charge throughout the chamber without intermediate vacant spaces between the charge and the wall of the chamber, said chamber being adapted to provide space to accommodate an enlarged smelting zone and to provide peripheral space for a large number of tuyères.

2. A blast furnace comprising a smelting chamber, a vertical shaft extending upwardly from

said chamber, said shaft and chamber being adapted to receive and confine a charge of material to be smelted, an opening for charging material into the top of said shaft to substantially fill the shaft and chamber, a series of tuyères discharging through the wall of the chamber in a tuyère plane located sufficiently below the base of the stack as to avoid extension of the smelting zone from the chamber into the stack, and a hearth providing a crucible for receiving molten metal at the bottom of said chamber, said chamber having its wall tapered inwardly and upwardly at an angle not substantially less than 65 degrees to the horizontal so as to provide space to accommodate an enlarged smelting zone.

3. A blast furnace comprising a smelting chamber, a vertical shaft extending upwardly from said chamber, said shaft and chamber being adapted to receive and confine a charge of material to be smelted, an opening for charging material into the top of said shaft to substantially fill the shaft and chamber, a series of tuyères discharging through the wall of the chamber in a tuyère plane located sufficiently below the base of the stack as to avoid extension of the smelting zone from the chamber into the stack, and a hearth providing a crucible for receiving molten metal at the bottom of said chamber, said chamber having its wall tapered upwardly and inwardly from the hearth to the base of the stack, and said tuyère plane being located not substantially above 30 percent of the vertical height of said chamber.

4. A blast furnace comprising a smelting chamber, a vertical shaft extending upwardly from said chamber, said shaft and chamber being adapted to receive and confine a charge of material to be smelted, an opening for charging material into the top of said shaft to substantially fill the shaft and chamber, a series of tuyères discharging through the wall of the chamber in a tuyère plane located sufficiently below the base of the stack as to avoid extension of the smelting zone from the chamber into the stack, and a hearth providing a crucible, for receiving molten metal at the bottom of said chamber, said chamber having its wall tapered upwardly and inwardly from the hearth to the base of the stack at an angle not substantially less than 65 degrees and not substantially more than 80 degrees with the horizontal and said tuyère plane being located not substantially above 30-percent of the vertical height of said chamber.

5. A blast furnace comprising a smelting chamber, a vertical shaft extending upwardly from said chamber, said shaft and chamber being of circular transverse cross-section and adapted to receive and confine a charge of material to be smelted, an opening for charging material into the top of the stack to substantially fill the shaft and chamber, a series of tuyères discharging through the wall of the chamber in a tuyère plane located a substantial distance below the bottom of the stack so as to avoid extension of the smelting zone from the chamber into the stack, said tuyères being directed downwardly toward the hearth of the furnace, and a hearth providing a crucible for receiving molten metal at the bottom of said chamber, said chamber having its wall tapered upwardly and inwardly between the tuyère plane and the stack at an angle not less than the angle of repose of the material so as to provide space to accommodate an enlarged smelting zone.

6. A blast furnace comprising a smelting

chamber, a vertical shaft extending upwardly from said chamber, said shaft and chamber being of circular transverse cross-section and adapted to receive and confine a charge of material to be smelted, an opening for charging material into the top of the stack to substantially fill the shaft and chamber, a series of tuyères discharging through the wall of the chamber in a tuyère plane located a substantial distance below the bottom of the stack so as to avoid extension of the smelting zone from the chamber into the stack, said tuyères being directed downwardly toward the hearth of the furnace, and a hearth providing a crucible for receiving molten metal at the bottom of said chamber, said chamber having its wall tapered upwardly and inwardly between the hearth and the stack and the ratio of the volume of the chamber between the tuyère plane and the stack to the volume of the stack for an equal rise in height being not substantially less than 2.73:1.00.

7. A blast furnace comprising a smelting chamber, a vertical shaft extending upwardly from said chamber, said shaft and chamber being of circular transverse cross-section and adapted to receive and confine a charge of material to be smelted, an opening for charging material into the top of the stack to substantially fill the shaft and chamber, a series of tuyères discharging through the wall of the chamber in a tuyère plane located a substantial distance below the bottom of the stack so as to avoid extension of the smelting zone from the chamber into the stack, said tuyères being directed downwardly toward the hearth of the furnace, and a hearth providing a crucible for receiving molten metal at the bottom of said member, said chamber having its wall tapered upwardly and inwardly between the hearth and the stack at an angle not substantially less than 65 degrees to the horizontal and the ratio of the volume of the chamber between the tuyère plane and the stack to the volume of the stack for an equal rise in height being not substantially less than 2.73:1.00, and the tuyère plane being located not substantially above one-quarter of the vertical height of said chamber.

8. A blast furnace comprising a smelting chamber, a vertical shaft extending upwardly from said chamber, said shaft and chamber being of circular transverse cross-section and adapted to receive and confine a charge of material to be smelted, an opening for charging material into the top of the stack to substantially fill the shaft and chamber, a series of tuyères discharging through the wall of the chamber in a tuyère plane located a substantial distance below the bottom of the stack so as to avoid extension of the smelting zone from the chamber into the stack, said tuyères being directed downwardly toward the hearth of the furnace, and a hearth providing a crucible for receiving molten metal at the bottom of said chamber, said chamber having its wall tapered upwardly and inwardly between the hearth and the stack and the ratio of the vertical distance between the tuyère plane and the base of the stack and the diameter of the stack being not substantially less than 1.00:0.78.

not substantially less than 1.00:0.75.

9. A blast furnace comprising a smelting chamber, a vertical shaft extending upwardly from said chamber, said shaft and chamber being of circular transverse cross-section and adapted to receive and confine a charge of material to be smelted, an opening for charging material into the top of the stack to substantially fill the shaft

and chamber, a series of tuyères discharging through the wall of the chamber in a tuyère plane located a substantial distance below the bottom of the stack so as to avoid extension of the smelting zone from the chamber into the stack, said tuyères being directed downwardly toward the hearth of the furnace, and a hearth providing a crucible for receiving molten metal at the bottom of said chamber, said chamber having its wall tapered upwardly and inwardly between the hearth and the stack at an angle not substantially less than 65 degrees to the horizontal and the ratio of the vertical distance between the tuyère plane and the base of the stack and the diameter of the stack being not substantially less than 1.00:0.78.

10. A process of smelting which comprises confining in a closed chamber the charge to be smelted in the form of an inverted funnel so as to define a base portion in the shape of a truncated cone and a vertical column of restricted diameter extending upwardly from the base portion, the walls of the confining chamber completely confining and lying substantially in contact with the body of charge without intervening spaces, said charge comprising a metal-bearing material, a fluxing material and a solid carbonaceous fuel, injecting a large volume of air into the base portion adjacent its bottom at a multiplicity of circumferentially-spaced points so as to produce a smelting zone located wholly within the

base portion and a high gas pressure area at and below the junction of the column with the base and overlying the smelting zone, whereby to increase the pressure and temperature in the smelting zone so as to give maximum concentration of carbon monoxide in the gases when the charge of carbonaceous material, carbon dioxide and carbon monoxide are in equilibrium within the smelting zone, and to increase the temperature of the slag.

15 11. A process of smelting which comprises confining the charge within the walls of a blast furnace in the form of a vertical column terminating in an enlarged base having downwardly and outwardly sloping sides completely confined by and wholly lying in close contact with the walls of the furnace without intervening air spaces and injecting air blasts into the base in such quantity and at such a level below the lower 20 end of the column so as to produce an enlarged smelting zone lying wholly within the interior of the base and entirely below the lower end of the column the transverse area of the base at the points of injection of the air blasts being substantially greater than its area at the junction of the base with the column, whereby to accelerate the descent of the charge through the column and to increase the pressure of combustion gases within the base.
